UNITED STATES PATENT OFFICE.

ROY COFFMAN, OF COLUMBUS, OHIO, ASSIGNOR TO THE AMERICAN AUTO BRASS COMPANY, OF COLUMBUS, OHIO, A CORPORATION OF OHIO.

DESIGN FOR A VEHICLE-LAMP.

No. 38,307.

Specification for Design.

Patented Nov. 6, 1906.

Application filed September 13, 1906. Serial No. 334,546. Term of patent 7 years.

To all whom it may concern:

Be it known that I, Roy Coffman, a citizen of the United States, residing at Columbus, in the county of Franklin and State of Ohio, have invented a new, original, and ornamental Design for Vehicle-Lamps, of which the following is a specification, reference being had to the accompanying drawings, forming part thereof.

In the drawings, Figure 1 is a view illustrating one side of the lamp. Fig. 2 is a

view illustrating the opposite side of the lamp, and Fig. 3 is a rear end elevation of said lamp.

I claim—

The ornamental design for a vehicle-lamp, as shown.

ROY COFFMAN.
